UNITED STATES PATENT OFFICE.

ROBERT CUNNINGHAM, OF BROOKLYN, NEW YORK.

SANITARY LINING FOR GARBAGE-RECEPTACLES.

1,181,506.

Specification of Letters Patent.

Patented May 2, 1916.

Application filed March 23, 1914. Serial No. 826,704.

To all whom it may concern:

Be it known that I, ROBERT CUNNINGHAM, a citizen of the United States, residing at Brooklyn, in the county of Kings and State 5 of New York, have invented certain new and useful Improvements in Sanitary Linings for Garbage-Receptacles, of which the following is a full, clear, and exact specification.

10 This invention relates to receptacles for garbage and has for its object to provide a sanitary lining for such receptacles which lining may be removed with the contents of the receptacle, thus keeping the inner surface of the receptacle clean and free from germs.

Another object is to provide a lining of the kind described which may be made of inexpensive material and yet have the 20 requisite strength and durability.

A further object is to provide a lining which may be folded into compact form so as to occupy a minimum space in transportation and storage.

25 Other objects will appear as the description proceeds.

The invention will be first hereinafter described in connection with the accompanying drawings, which constitute a part of 30 this specification, and then more specifically defined in the claim at the end of the description.

In the accompanying drawings, wherein similar reference characters are used 35 throughout the several views to designate corresponding parts:—Figure 1 is a central vertical section of a lining made in accordance with my invention. Fig. 2 is a plan view of the same, the position of the attaching tabs when bent down into right angles with the walls of the lining being indicated in dotted lines. Fig. 3 is a central vertical section of a garbage receptacle with my lining attached thereto, and Fig. 4 is a plan 40 view of the lining folded flat for storage and transportation.

Referring more particularly to the drawings, A designates the walls and B the bottom of the lining which is preferably made 50 of paper treated with paraffin or the like to make it impervious to water. The lower end portion of the wall member A is folded inward as at a and glued or otherwise se-

curely fastened to the peripheral portion of the bottom B. The inwardly folded portion 55 a is made amply wide, as best shown in Fig. 2, in order to provide plenty of space for the application of the adhesive substance for making a secure fastening which will hold under the weight of the contents of the lining 60 when the same is removed from the garbage receptacle, and also for preventing leakage at the joint.

The upper edge portion of the wall member is folded down upon itself, as at a', to 65 provide reinforcement at the exposed upper edge of the lining. At regular intervals around, the upper edge of the lining tabs C are secured as at c by glue or other suitable means. These tabs may be made of 70 heavy waxed paper and normally extend well beyond the edge of the lining, as shown in Fig. 1. When the lining is inserted in a garbage receptacle D, as illustrated in Fig. 3, these tabs are bent or folded down over the 75 upper edge of the receptacle to prevent the lining from sagging.

For storage and transportation purposes, the lining may be folded flat, as shown in 80 Fig. 4, the upper portion of the wall member A being folded or doubled upon itself and the bottom B and lower portion of the wall member folded over upon said wall member, so that the bottom need not be folded at all, thus leaving the joint between 85 said bottom and wall member unimpaired by the folding operation. In other words, the linings when folded in the manner indicated will not tend in any degree to loosen the joint between the bottom and inwardly 90 folded lower end portion a of the wall member, as might result from folding the bottom upon itself.

It will be readily understood that when 95 the lining is applied to a garbage receptacle, as illustrated in Fig. 3, said lining will protect the inner surface of the receptacle from the garbage which will be placed in and removed with the lining, a new lining being inserted after the receptacle is emptied each 100 time.

Having thus described my invention, what I claim as new and desire to secure by Letters Patent of the United States is:—

A cylindrical lining for garbage receptacles and the like, made of paper and hav-

ing its upper edge portion thicker than its walls, and spaced paper tabs attached to said upper edge portion of the lining and projecting therefrom for folding over the upper edge of the receptacle to support the lining therein.

In testimony whereof I have signed my

name to this specification in the presence of two attesting witnesses.

ROBERT CUNNINGHAM.
